UNITED STATES PATENT OFFICE.

ALEXANDRE ZEITLIN, OF NEW YORK, N. Y., ASSIGNOR OF ONE-FOURTH TO JACK HELLER, ONE-FOURTH TO JOSEPH RIFKIN, AND ONE-FOURTH TO SAMUEL HELLER, ALL OF NEW YORK, N. Y.

FALL-CHECKING DEVICE FOR AIRCRAFT.

1,426,331.

Specification of Letters Patent. Patented Aug. 15, 1922.

Application filed June 17, 1921. Serial No. 478,368.

To all whom it may concern:

Be it known that ALEXANDRE ZEITLIN, citizen of the Georgian Republic, residing at New York city, New York, has invented a 5 new and useful Improvement in Fall-Checking Devices for Aircraft, of which the following is a specification.

My invention relates to a stabilizing device and lifting propeller for air craft and 10 has particular reference to such a combination of parts which may be employed to maintain the equilibrium of a falling aeroplane and simultaneously offer substantial resistance to the rapid descent of such a 15 body.

The object of the present invention is to provide a telescoping parachute to be carried by the present type of air craft and which may be used as a plane during forward flight, but capable of being extended, 20 in case of emergency so as to check the descent, of the machine.

Another object of this invention is to provide a helicopter driven by an independent motor and which may extend below 25 the aeroplane, to substantially assist in breaking the rapid descent of the falling craft.

With these and other objects in view the present invention consists in the combination 30 and arrangement of parts hereinafter clearly set forth and illustratively exemplified in the accompanying drawing, wherein:

Fig. 1, is a side elevational view of an air craft equipped with my invention.

Fig. 2, is a plan view of the telescoping 35 parachute.

Fig. 3, is a substantially vertical sectional view taken on the lines 3—3 of Fig. 2.

Fig. 4, is a sectional view taken on the 40 lines 4—4 of Fig. 2, showing the supporting frame for the extensible sections of the parachute.

Referring to the drawing 10 indicates the fuselage of an air craft and provided with 45 the usual cock-pit 11 having a motor 12 and operator's seat 13 housed therein. A driving propeller 14 of the well known type is mounted forward of the nose of the cock-pit 11 and is driven by the motor 12. 50 Suitable wings 15 extend laterally from each side of the body 10; these wings may be arranged either as monoplanes or biplanes depending upon the type of craft used. The body is supported, when at rest upon the

ground, on wheels 16 carried beneath the 55 body and rearwardly of the cock-pit 11. The tail 17 of the craft is made up of a frame work of metal which may be of any strong type and provided with the usual stays and cross pieces.

Carried by the tail piece 17 rearwardly of the cock-pit 11 is a superstructure 18 adapted to support a telescoping parachute 19 which is circular in form and slightly elevated in the center to provide a cone. The 60 65 parachute 19 is secured to the superstructure 18 by means of a circular frame 20 comprising an annular grooved member 21 having inwardly projecting radial spokes 22 which are secured together at their inner ends by a collar 23. The collar 23 is received by a central post 23^a projecting upwardly from the superstructure 18 and it is attached thereto by any suitable means, not shown. Fixed to the frame 20 and extending substantially one half of the circumference 70 thereof is a semicircular disk 24. This disk 24 is arranged to cover the rearward half of the frame 20 as that the grooved portion of the latter will form a marginal edge about 75 the surface of the disk 24. Slidably mounted upon the forward half of the frame 20 are two quarter segments 25 provided about their outer edge with a depending tongue 80 85 90 95 26 adapted to rest in the groove of the member 21. These segments 25 are extensible over the frame 20 and disk 24 so that by moving each quarter away from each other and toward the rear of the frame 20 the parachute 19 is closed and is used as a plane to assist in supporting the machine when in flight.

In order to facilitate the opening and closing of the parachute 19 the quarter segments 25 are each provided with stud plates 27 having studs 28 extending from their upper surfaces and arranged so that there will be one peg or stud 28 at each of the two straight edges of the plates 27 adjacent the periphery thereof. Attached to the upper 100 end of the post 23 and extended axially of the machine is a control bar 29 having guide thimbles 30 extending through openings in opposite ends thereof. The rearward thimble 30 projects through the disk 24 and the 105 forward thimble 30 receives recesses provided in the edge of each of the abutting quarter disks 25. In order to control the

arcuate movements of the disks or segments 25^a guide wire 31 attached to each of the forward studs 28 extends to the forward thimble 30 and are threaded through the 5 opening therein and attached to one arm of a T shaped lever 32 which is pivoted in the frame work of the superstructure 18. This connection controls the opening of these segment disks 25 to a position shown in Fig. 2. 10 The rearward movements or telescoping of the segment disks 25 are likewise controlled by wires 33 attached at one of their ends to the rearward studs 28 and then being threaded through the rearward thimble 30 15 to the other arm of the T lever 32. It will be noted that by rocking this lever 32 the wires will be drawn through one of the thimbles 30 and in this way the segments 25 are moved over the frame 20 and disk 24 to 20 their respective positions. A slide rod 34 is pivoted to the stem of the T lever 32 and extends forward to a workable position within reach of the operator's seat 13.

Axially aligned with the parachute 19 and 25 depending from the tail piece 17 between the wheels 16 is a helicopter or lifting propeller 35 which is driven by an auxiliary motor 36. This motor may be of the internal combustion type or an electrically controlled motor receiving its current from storage batteries. Suitable wiring connected to an automatically operated switch could be provided to automatically throw the motor 36 into operation following the 30 stopping of the main driving motor 12.

As previously explained, the parachute 19 is in closed position when the machine is being propelled forward in the usual manner, but assuming that trouble has centered in 40 the motor 12 which caused it to stop and the craft immediately began to descend, the operator could instantly operate the lever 32 by drawing forward the slide rod 34 and the forward wires 31 would pull the segment disks toward each other until the full 45 circular surface of the frame 20 is closed. The parachute 19 is then in its open position and supports the craft against rapid descent in the manner peculiar to this type of device. 50 In this way the machine would remain in upright position throughout its fall or in other words the parachute would exercise a stabilizing effect upon the craft. In addition to the support received from the extended 55 parachute the lifting effect of the

helicopter would further aid in breaking the downward travel of the descending machine and by the time the craft approached the earth its downward speed may be practically overcome.

What I claim is:

1. In an air craft, a combination plane and parachute, comprising a stationary annular supporting frame, a relatively fixed semicircular solid disc portion carried by 65 said frame, and additional solid disc portions slidably supported in said frame and movable relatively to the fixed portion.

2. In an air craft, a combination plane and parachute, comprising a stationary annular supporting frame, a relatively fixed semicircular solid disc portion carried by 70 said frame, additional solid disc portions guidely supported in said frame and movable relatively to the fixed disc, and means 75 for imparting movement to said additional disc portions, whereby a complete solid annular supporting surface may be effected.

3. An air craft, in combination superstructure towering above said craft and provided with a circular frame at its upper end, a parachute including a semicircular disk fixed to the rearward portion of said frame, extensible segmental disks slidably supported upon said frame and adapted to 80 be moved to overlie the forward portion of said frame to complete a circular supporting surface, means for moving said segmental disks toward and away from each other to 85 close or open said parachute.

4. An air craft, in combination a telescoping parachute including a semicircular disk having its surface inclined upwardly toward a central point, two segmental sections movable relatively to said first named disk and 95 in a direction which is toward or away from each other to form a complete circular surface with the semicircular disk or to overlie the latter, and guide wires attached to opposite radial edges of said segmental sections to control the arcuate movements of 100 the latter.

In testimony whereof, ALEXANDRE ZEITLIN has signed his name to this specification, this 25th day of May 1921.

ALEXANDRE ZEITLIN.
